ELECTRICAL MUSICAL INSTRUMENT

Laurens Hammond, Chicago, Ill.

Application June 26, 1939, Serial No. 281,077

20 Claims. (Cl. 84—1.25)

My invention relates generally to electrical musical instruments, and more particularly to an improved instrument of this character in which the tone signals are electrically produced by rotating tone wheels used either as generators, or as modulators of a super-sonic carrier frequency.

It is a comparatively difficult and expensive operation to form tone wheels of rotary electromagnetic or electrostatic generators or modulators with such accuracy that the signal produced contains only the desired fundamental frequency and a series of predetermined harmonic frequencies, and which is free from objectionable noise. In endeavoring to form the tone wheel in such manner as to generate not only the fundamental, but also the higher harmonic frequencies to produce a tone of complex quality, it is found to be nearly impossible to eliminate from the signal various noises and unwanted frequencies by any means which can be used practically in the quantity production of such instruments.

It is of course desirable, in the rendition of certain kinds of music, that the tones be rich in harmonics, and unless the rotating generator or modulator which supplies the fundamental frequency can also be made to supply the higher harmonic frequencies, it is necessary to provide a relatively expensive switching mechanism whereby the harmonics may be derived from other generators and combined with the fundamental frequency to produce a note of the desired tone quality. In order to provide a full range of harmonics in an instrument of the latter character, a relatively large number of generators are required, more than the number required for supplying only the fundamental frequencies. To reduce the number of generators required, practical considerations dictate the use of harmonics which are of the tempered musical scale.

In the present invention, I have provided means whereby a rotating generator may be made to supply a signal which is rich in harmonics, and which, nevertheless, can be very easily and inexpensively manufactured. Although the instrument may be made without the use of switching mechanism for adding harmonics, I have illustrated the invention as including coupler switching means. When the latter are used, the tone wheels may be designed to generate less harmonically developed tones, and the coupler switches used to build up the desired degree of brightness in the tone quality, thereby increasing the range of tone coloring available.

It is thus an object of my invention to provide an improved electrical musical instrument

in which rotary generators are employed to provide tone signals each consisting of a fundamental frequency and a large number of partials, but which is free from noise and extraneous frequencies.

5 A further object is to provide an improved electrical musical instrument incorporating rotary signal generators in which all of the generators rotate at a speed in the order of seven revolutions per second.

10 A further object is to provide an improved electrical musical instrument employing rotary signal generators which are utilized to modulate a radio frequency carrier wave, and in which a 15 radio receiving set may be employed to detect and amplify the modulated carrier wave.

A further object is to provide an improved electrical musical instrument in which the attack and decay of the notes is controlled by the operation of the playing keys.

20 A further object is to provide an improved electrical musical instrument playable by keys, wherein the intensity of the notes sounded may be determined by the extent of depression of the 25 keys.

A further object is to provide an improved electrical musical instrument in which the tone quality may be varied throughout a considerable range, and by which tones of high harmonic development may be produced.

30 A further object is to provide an improved tone wheel signal generating system in which certain inaccuracies in the form and speed of rotation of the tone wheels are permissible, and in fact, are desirable.

35 A further object is to provide an improved electrical musical instrument which is touch responsive.

40 A further object is to provide an improved electrical musical instrument which may be manufactured at very small expense and which will produce beautiful, rich vibrato tones, and by which the player may adequately render the great works of classical and modern composers.

45 A further object is to provide an improved means for producing a vibrato effect.

Other objects will appear from the following description, reference being had to the accompanying drawings in which:

50 Figure 1 is a schematic diagram of representative portions of the instrument, a portion of the keyboard and the generating system being shown in transverse section;

55 Figure 1a is a fragmentary sectional view taken on the line 1a—1a of Figure 1;

Figure 2 is a longitudinal sectional view of a portion of the generator assembly;

Figure 3 is a longitudinal sectional view of one of the pickup electrodes;

Figure 4 is a transverse sectional view of a pickup electrode taken on the line 4—4 of Figure 3;

Figure 5 is a chart showing the gear ratios and other constructional factors of the generating system;

Figure 6 is a wiring diagram showing representative portions of the key switch circuits;

Figure 7 is a fragmentary sectional view showing a vibrato producing apparatus;

Figure 8 is a transverse sectional view taken on the line 8—8 of Figure 7;

Figure 9 is a fragmentary sectional view of a modified form of vibrato producing apparatus; and

Figure 10 is a transverse sectional view taken on the line 10—10 of Figure 9, and showing a plurality of the modified vibrato producing devices together with a control circuit therefor.

In general, the instrument comprises a tunable radio frequency oscillator which supplies a carrier wave to a key controlled variable condenser of unique construction, the radio frequency carrier wave passing through this condenser upon operation of the key, to be modulated by passing through a circuit having a capacity varied by a rotating tone wheel. The modulated carrier wave thus produced is demodulated, amplified, and translated into sound. One of the distinctive features of the invention is that all of the rotary modulators, or tone wheels, rotate at a speed near seven revolutions per second, so that any irregularities in the tone wheel form will result in introducing vibrato frequencies rather than dissonant and noise frequencies.

Referring to Figure 1, the instrument comprises a shielded radio frequency oscillator 10 which may be of any suitable construction, shown as comprising an electron discharge device 12 having a tuning mesh consisting of an inductance 14 and variable condenser 16 in its output circuit. The output of the oscillator 10 is connected by a conductor 18 with a metallic bus bar 20, so that the potential of the latter with respect to ground is varied at the radio frequency of oscillation. The bus bar 20 forms a plate common to a plurality of variable condensers, and for this reason, the oscillator 10 should be of a type well known in the art, whose frequency of oscillation is not appreciably affected by such variation in the impedance of its output circuit.

A wedge-shaped sheet 22 of mica, micarta or the like, is secured to the bus bar 20 and is adapted to be engaged by flexible metal strips 24 which are attached to each of the keys of the manual. In Figure 1, but two keys, E₁ and E₂ are illustrated as representative of the 72 or more keys of the complete instrument. These keys are provided for controlling the notes E₁ and E₂ respectively of the tempered musical scale which have frequencies 82.407 and 164.81 respectively. The keys are diagrammatically indicated as pivoted upon a common rod 26 and are normally held in uppermost position by compression coil springs 28. A suitable felt stop strip 29 attached to a rail 30 limits upward movement of the keys, while their downward movement is limited by a felt strip 31. The flexible metal strips 24 are secured to the keys by insulating pads 32, being thereby suitably insulated from any metal portion of the keys.

When the keys are in their uppermost positions, the flexible metal strips 24 make contact with a grounded conductor 34. As the key is depressed, the ground connection with the strip 24 is broken and the latter is pressed against the insulating sheet 22 so that it is progressively flexed and flattened against said sheet. The extent of depression of the key thus controls the capacity of the condenser formed by the flexible strip 24 and the bus bar 20, and thereby determines the amplitude of the radio frequency signal transmitted through the flexible strip 24.

The flexible strips 24, as shown in Fig. 1a, may be tapered, or may be made of any other shape necessary to secure the desired variation in capacity as the key is depressed. Because the loudness of a sound does not vary directly with its amplitude, but instead varies substantially logarithmically, it will generally be desirable that the capacitance between the strip 24 and the bus bar 20 increase at an accelerating rate as the key is depressed. This may be accomplished in part, or wholly, either by having the insulating sheet 22 vary in thickness, as indicated in Fig. 1, or by having the strip 24 vary in width, or by both of these methods.

The flexible strips 24 may be made of sufficiently resilient material so that they are capable of returning the keys, thus eliminating the necessity of providing other key return means, such as the springs 28.

By this arrangement the keys are touch responsive, that is, if the key is struck a sharp blow, the note will commence with a percussive attack, while if the key is pressed down rather slowly, the attack of the tone will be correspondingly slow. Furthermore, the intensity of the tones may be maintained at any desired level by holding the keys partially depressed. For the latter function it is desirable that the key-return springs preferably be relatively strong and short, so as to afford a sufficiently variable resistance to depression of the keys to make it feasible to hold the keys partially depressed.

The flexible strips 24 of the keys E₁ and E₂ are connected respectively with groups of switch contacts 36 and 38 by conductors 37 and 39 respectively. A similar set of switch contacts 40 are adapted to be connected by a conductor 41 with a flexible strip 24 associated with some other key such as A₀. Each of the conductors such as 37, 39 and 41 is connected to ground by a resistor 42 shunted by a condenser 43, thus forming a shunt impedance load for the key completed circuit. The contacts 36, 38 and 40 are adapted to be engaged by flexible switch arms 46, 48 and 50 respectively, there being such switch arm for each of the contacts of these groups, although only one switch arm for each group is shown in Figure 1. The switch arms form parts of two-way switches, the other contacts of the switches being provided by grounded contacts 52.

Each of the switch arms 50 is connected to an electrode 54 which is secured in a metallic sleeve 56 (Figs. 3 and 4), but insulated therefrom by insulation 58. The insulation 58 is preferably a molded plastic which is formed in the sleeve 56 with the electrode 54 inserted therein so that the sleeve, insulation, and electrode, form a rigid unitary assembly.

The sleeve 56 is supported in a bushing 60 which is peened to a plate 62 forming a shielding housing for the tone wheel modulating apparatus. The sleeve 56 has a longitudinal groove 64 formed

therein and is secured in adjusted position in the bushing 60 by a set screw 66, the end of which projects into the groove 64. The sleeve is also provided with a flange 68 by which the sleeve may be engaged by a suitable tool used in adjustably positioning it in the bushing 60.

The electrode 54 preferably has a wedge-shaped end 70 which lies in close proximity to the path of movement of the extremities of projections 72 formed on its associated tone wheel, such as the tone wheel 74E₂.

Figure 6 shows a representative portion of the key switch control circuits, and for purposes of illustration, in addition to the key E₁, keys E₂, B₂, E₃, G₃#, B₃ and E₄ are shown. These latter keys are for notes harmonically related to the note E₁, being the second, third, fourth, fifth, sixth and eighth harmonics of the note E₁.

It will be noted that each of these keys is adapted to be connected to an electrode 54 associated with a tone wheel bearing a number corresponding to that of a key preceded by the reference character 74, such connection being made by switches 48 adapted to be operated by a coupler or stop 49 for the fundamental frequency. Similarly, switches 46 operated by the stop 49 for the second harmonic, are adapted to connect the flexible strips 24 with electrodes of tone wheels generating twice the frequency of the fundamental, such connection being effected by operation of the gang switch controlled by the stop 49 for the second harmonic. In a similar manner, circuits and coupler switches may be provided so that depression of the keys will render effective the tone wheels generating signals of fundamental frequencies corresponding to the third, fourth, fifth, and if desired, also the sixth, eighth, etc. harmonics of the notes of the depressed keys.

Since each of the tone wheels generates a signal which in itself is rich in harmonics, it will ordinarily not be practical to provide stops 49 and gang switches operated thereby, for more than the first few harmonics. In fact, excellent musical results may be obtained without the use of any stop operated switches.

As best shown in Figure 2, there are a plurality of tone wheels designated with the reference character 74 and followed by an appropriate note designation. Each group of these tone wheels is secured to a common shaft 76 which is mounted for rotation in bearings 78 carried by frame plates 82 which are insulated from and secured to the casing plate 62, and are held in properly spaced relation by suitable spacing rods 84 and notched strips 86, (Fig. 1), the notches of which are held in engagement with the plates 82 by wires 88. There is a shaft 76 provided for each of the notes of an octave and there will thus ordinarily be twelve shafts 76, of which only two are shown in Figure 2. Each of the shafts thus carry a number of tone wheels 74 determined by the number of octaves encompassed by the instrument, plus one or more additional tone wheels, to provide the additional harmonic frequencies desired, if the stop arrangement of Figure 6 is utilized.

In the particular construction shown in Figure 2, six tone wheels are shown on each shaft 76 and these tone wheels will thus provide the signals for the corresponding notes of the six octaves—for example, all of the E's. These tone wheels have therefore been given reference characters 74E₀ to 74E₅, while the six wheels on the adjacent shaft for the F's of the instrument have been correspondingly marked 74F₀ to 74F₅.

The shafts 76 are rotated preferably from a

synchronous motor driven shaft 90 mounted in bearings 92 supported by the frame plates 82. Driving gears 96 secured to the shaft 90 mesh with driven gears 98 rotatably mounted upon the shafts 76. A resilient and frictional driving connection between each of the driven gears 98 and its associated shaft 76 is provided by coil springs 100 compressed between the driven gear 98 and the adjacent tone wheels. These springs 100 have their ends turned inwardly so as to provide for smooth sliding engagement with the opposed surfaces of the tone wheels 74E₅ and 74E₆ and driven gear 98.

The springs 100 are under initial compression so that there is sufficient friction between their end turns and the tone wheels and gear 98 to provide a torque normally sufficient to drive the shaft 76. In the event, however, that the rotation of the tone wheels should be obstructed in some manner, or an unusually abrupt change in speed of the driven gear should take place and thus put an unusual strain upon the driving connection, the ends of these springs 100 may slip and thus prevent damage to the parts of this assembly.

The modulated signal is transmitted from the tone wheel 74 to shafts upon which they are mounted and is thus conducted to the frame plates 82, since all of the tone wheels and their driving gears and supporting frame plates are in electrical connection, but are insulated from the casing 62. A shielded conductor 106 (Fig. 1) connects this assembly to the input of a radio frequency amplifier and detector 107 (Fig. 1), shown conventionally as including a tube 108 for the radio frequency amplifying stage, and a tube 110 for the detector stage.

The radio frequency stage is provided with tuning condensers 112 and 114, by which the amplifier may be tuned to the frequency of the radio frequency oscillator 10. The output of the detector is supplied to suitable adjustable resonant output circuits 116, through a volume control apparatus 118 to a power amplifier 120, and hence to an electroacoustic translating means such as a speaker 122.

Since any suitable radio receiving apparatus may be utilized, it is believed to be unnecessary to describe these parts in detail. In fact, in some installations, it may be practical to couple the conductor 106 to the antenna circuit forming the input of a customary radio receiving set. In such case, by tuning the receiving set to the frequency generated by the oscillator 10, the signals supplied by the conductor 106 may be economically amplified and translated into sound.

As previously indicated, one of the novel features of my invention resides in the fact that all of the tone wheels are rotated at a frequency near seven revolutions per second, by virtue of which it is possible to manufacture the instrument at very low cost. The low cost is possible because it is not necessary to make and assemble the tone wheels with a high degree of precision, as is necessary when the tone wheels are rotated at other speeds.

From numerous experiments with tone wheel generators employing electromagnetic or electrostatic pickups, I have found that it is extremely difficult to cause the wheels to generate only the frequencies corresponding to the tooth formation whenever the tone wheel irregularities are so formed as to produce a signal having a high harmonic content.

From the general theory of tone wheels, it ap-

pears that a tone wheel revolving at a constant speed will give rise to frequencies in the output circuit of the pickup device, which frequencies are exact harmonics of the speed of rotation of the wheel. For example, a wheel having sixty-four teeth rotating at 20 c. p. s. is capable of producing frequencies of 20, 40, 60, 80, etc. c. p. s., the sixty-fourth harmonic, of 20, or 1280 cycles being one of the frequencies of this series. If the wheel could be manufactured with mathematical accuracy, the only frequencies present in the output would be 1280, 2560, 3840, c. p. s.—all being harmonics of the 1280 cycle frequency. Unfortunately, however, practically unavoidable inaccuracies in the form and mounting of the wheels causes other frequencies to appear in the output, these additional frequencies differing from the intended frequencies by steps of 20 cycles, the rotation frequency. Thus, instead of getting 1280 cycles with no other frequencies near this value, it will be found that sum and difference frequencies between the rotation frequency of 20 cycles and the fundamental tone wheel frequency of 1280 cycles, such as 1240, 1260, 1300, 1320 cycles, etc., will appear, these latter frequencies being musically undesirable and constituting noise with respect to the intended frequencies.

On the other hand, I have found by extended experimentation with vibratos and tremulants, that very desirable musical effects can be obtained by varying the frequency of a musical tone through a small frequency range at a rate of about 7 c. p. s. This variation may be discontinuous, i. e., accomplished by a sudden change from one frequency to the other, or may be made accurately at a sinusoidal rate.

The theory of cyclical variations in frequency of a musical tone at a vibrato periodicity has been investigated, disclosing a curious fact from mathematical considerations. Assuming that a generator, such as a vacuum tube oscillator, is oscillating at an average frequency of 1000 c. p. s. and that this frequency of oscillation is periodically altered by connecting and disconnecting an additional condenser in the tuning circuit, cyclically, seven times per second. Upon analyzing the output of such oscillator, using a harmonic analyzer to determine what frequencies are present in the output, it is found that this experiment bears out the theory that the output contains no frequency of 1000 cycles because all frequencies present in the output must be multiples of seven, and 1000 is not a multiple of seven. Thus, frequencies close to 1000, but divisible by seven, such as frequencies of 994, 1001, 1008, 1015, etc., may appear. The energy distribution on these various frequencies will be determined by the amount of frequency shifting which is caused seven times per second by a frequency changing device such as the intermittently connected condenser in the tuning circuit of the oscillator. Since such frequency shifting device operates in a discontinuous manner, and not sinusoidally, other frequencies in the neighborhood of the harmonics of 1001, namely, 2002, 4004 c. p. s. etc., and other frequencies which differ from the frequencies 2002 and 4004 by the number seven, as for example, 2009, 2016, etc., and 4011, 4018, etc., may appear.

An analysis of the effects obtained using tone wheels revolving at speeds in the order of seven revolutions per second may be deduced from the general considerations above pointed out. For example, in a generating system having a tone

wheel which is rotated at seven revolutions per second and has six teeth, all of the frequencies generated must be multiples of seven. If the teeth are evenly spaced and the wheel is made with mathematical accuracy, the only frequencies generated would be six times seven or 42 c. p. s., together with harmonics thereof, such as 84 cycles and 126 cycles, etc. If, however, the teeth are unevenly spaced, there will still be forty-two impulses per second on the average. But, the irregular sequence of impulses may be analyzed into different steady state frequencies which differ from 42 cycles, 84 cycles, or 126 cycles by seven or multiples of seven. Thus, 35 cycles, 49 cycles, 56 cycles, 91 cycles, 98 cycles, 119 cycles, 133 cycles, 140 cycles, etc., may be present.

Irregular spacing of the teeth in such tone wheel will be equivalent to varying the frequency cyclically seven times per second, and the musical effect in the tone which is produced will be perceived simply as a vibrato effect. If the wheel is not concentric, there will be a change in amplitude of the signal at a rate of 7 c. p. s., which will give rise to an effect which is usually referred to as a tremulant, because the change is particularly one of amplitude.

The net result of operating all of the tone wheels of the musical instrument herein disclosed, at a rate of about seven revolutions per second, will be that the wheels may be made inaccurately and still produce musically desirable tones. For this reason, the teeth or projections 12 on the tone wheels 14 are preferably intentionally spaced closer together on one side of the wheel than they are on the other, so that as the wheel is rotated at a generally uniform speed, the effect of vibrato will be automatically introduced.

In designing the gearing for driving the tone wheels of the instrument, it will of course be impossible to have all of the tone wheels revolve at exactly seven revolutions per second because the intervals of the tempered musical scale could not thus be obtained. This is an advantage rather than a detriment, since it will give rise to different vibrato rates for different notes. This is a highly desirable effect when two or more notes, as in a chord, are played simultaneously, since it tends to enable the listener to perceive the separate notes, and adds greatly to the richness and fullness of the chord.

In the chart, Figure 5, I have tabulated some of the physical constants which may be utilized in constructing the generator assembly, this chart applying particularly to the lowermost octave of the instrument, but by extrapolation being applicable to the complete assembly.

Column I gives the note numbers commencing with the lowermost note which may be played on the instrument. Column II gives the corresponding musical designations of the notes, while column III gives the theoretical frequencies of the notes of the lowest octave. Column IV gives the number of teeth on the tone wheels 14 for the lowest octave notes, it being understood that the number of teeth on the tone wheels for the higher octaves may be determined by successively multiplying the numbers given in this column by the factor two. Column V sets forth the theoretical speed at which the tone wheels should be rotated in order to produce the frequencies set forth in column III, while column VI is a tabulation of the gear ratios which may be employed in an instrument to cause the tone

wheels to rotate at the number of revolutions per second set forth in column VII. The gear ratios are computed upon the assumption that the synchronous motor driven shaft 90 rotates at a speed of 1200 R. P. M. Column VIII indicates the approximate deviation of the speed of revolution of the tone wheels set forth in column VII, as compared with their theoretically correct speed of revolution set forth in column V—the deviation being indicated in fractional parts of the theoretically correct speed.

It will be noted that the fractions of column VIII are in each instance very much smaller than the minimum difference in pitch which is perceptible to even the most discriminative ear.

From column VII of this chart, it will be observed that all of the tone wheels rotate at speeds between the minimum of 6.4815 and maximum of 8.1667 revolutions per second, and that the average speed of the tone wheels is near seven revolutions per second. As above pointed out, the fact that all of the tone wheels do not rotate at exactly seven revolutions per second is an advantage rather than a disadvantage.

The figures tabulated in Figure 5, especially the figures in columns IV, VI, VII and VIII are intended merely as illustrative, it being understood that considerable variations from these values are possible without materially affecting the over-all results obtainable from the instrument.

As above pointed out, any inaccuracies in the shapes of the tone wheel will not introduce noise frequencies, but instead, will result in the introduction of vibrato frequencies. However, if these inaccuracies are not great, the vibrato effect will be very slight, and it may therefore be desirable to provide means for introducing a more pronounced vibrato effect whenever such effect is desirable, due to the character of the music being rendered.

In Figure 7 is illustrated a simple mechanism for causing the introduction of pronounced vibrato frequencies, this mechanism comprising a counter-weighted disc 130 of magnetic material, eccentrically mounted upon a tone wheel shaft 76 so as to rotate therewith. There will be a disc such as 130, mounted upon each of the shafts 76 of the instrument. A shaft 132 having suitable bearings in the frame plates 82 carries a plurality of permanent magnets 134, which may be swung to the position indicated in full lines in Fig. 8, such that the poles of the magnet lie near the periphery of the disc 130. The shaft 132 is manually rotatable through an angle of approximately 90°, so that the magnets 134 may be shifted from their operative positions, as indicated in full lines in Figure 8, to their inoperative positions, as indicated in dotted lines in said figure, whenever the pronounced vibrato effect is not desired.

It will be understood that as the disc 130 rotates adjacent the poles of the magnet 134, it will, due to its eccentricity, be attracted and thus accelerated by the magnet during approximately one half revolution, and will be retarded during the remainder of its cycle. This application of alternate accelerating and retarding forces to the disc 130 will result in a slight periodic change in the speed of rotation of the shaft 76, such variation being permitted by the flexible coupling provided by the springs 100 through which the shafts 76 are driven. The variation in speed of rotation of the shafts 76 will of course

be at a vibrato periodicity and will result in the introduction of a pronounced vibrato effect in the music produced. When this pronounced vibrato effect is not desired, the shaft 132 may be rotated clockwise (Fig. 8) to swing the magnets 134 to the dotted line position, in which position the magnets will not have an appreciable effect upon the speed of rotation of the shafts 76. The degree of the vibrato effect may of course be varied by positioning the magnets at any desired position intermediate the full line and dotted line positions.

In Figures 9 and 10 is shown a modified form of vibrato producing mechanism, in which electromagnets, each comprising a core 140 and winding 142, are used in place of the permanent magnets. The cores 140 are rigidly secured to adjacent frame plates 82 and have poles 141 which lie adjacent the peripheries of the eccentric discs 130 secured to shafts 76. There is a small air gap between the poles 141 and the edge of disc 130 when the latter is closest to the poles, as shown in full lines in Fig. 10. The windings 142 are preferably connected in parallel to a suitable source of current 143 through a controlling switch and rheostat 144. By means of this switch and rheostat, the degree of energization of the windings 142 may be adjusted so that the degree of acceleration and retardation of the discs 130 may be varied to control the extent of vibrato.

In making commercial forms of the invention, it will be practical, to reduce the cost of the instrument, to omit the vibrato producing means shown in Figs. 7 to 10 inclusive. Instead, the tone wheels may intentionally be made with the teeth thereof nonuniformly spaced so that during each revolution of the tone wheel, the signal generated thereby will vary in frequency between a frequency which may be in the order of 1½% greater than the nominal frequency for the particular wheel and a frequency which is in the order of 1½% less than such nominal frequency. Such tone wheels may be constructed in a number of different ways to cause the spacing of the projections (or other irregularities) thereon to be more closely spaced on one side of the wheel than upon the other, or to be otherwise irregularly spaced.

For example, a blank may be stamped in which the projections are non-uniformly spaced about the periphery of the wheel. Thereafter the blank may have its periphery ground while the blank is rotated about its center so that the periphery will be very accurately concentric with the axis of rotation.

For the manufacture of the tone wheels disclosed herein, the tone wheel blank may be stamped or hobbed with its peripheral projections 72 uniformly spaced about the periphery. Then, after the hub has been pressed into and peened to the tone wheel, the tone wheel may be located and clamped by means engaging its periphery, and the bore through the hub of the tone wheel bored or reamed so as to be eccentric with respect to the periphery of the tone wheel. If the tone wheel is about two inches in diameter, the bore should be in the order of .015" eccentric with respect to the periphery of the wheel.

Thereafter, the tone wheel may be assembled on the shaft 76 and have its peripheral projections ground down until the tips of the projections are concentric with the axis of rotation of the shaft. This grinding operation will re-

sult in changing the effective angular spacing of the projections about the periphery of the wheel, so that adjacent projections on one side of the wheel will be spaced closer together than adjacent projections on the diametrically opposite side of the wheel.

This method of manufacture results in a tone wheel in which the spacing of the projections varies substantially harmonically. However, this is not essential, since the variation in spacing may be irregular. For example, the wheel may have sectors in which the projections are uniformly spaced angular distances less (by approximately 1½%) than the average spacing required, while in other sectors the projections are uniformly spaced by angular distances greater (by approximately 1½%) than the average spacing required to produce the note of the desired nominal frequency. In fact, the spacing of the projections may vary continuously or discontinuously, in any of a wide variety of different ways, without materially affecting the result.

An instrument thus constructed in which the projections or other irregularities on the tone wheels are unevenly spaced about the tone wheel peripheries, may be made capable of producing rich tones having the vibrato shift in frequency to a sufficiently pronounced degree that it will be unnecessary to provide additional means, such as those shown on Figs. 7 to 10, for causing a greater vibrato frequency shift.

It will therefore be apparent that by this method of forming the tone wheels and rotating them, the necessity for an extremely high degree of precision in the form of the tone wheels and in their concentricity is avoided, while at the same time the musical results obtained are greatly improved.

To those skilled in the art, it will be readily understood that the underlying principle of the invention may be utilized in making various other types of electrical impulse generators for electrical musical instruments. For example, the principle may be utilized in the production of the discs and drums proposed for use in photoelectric systems, wherein the alternate opaque and translucent portions, or the alternate dark and light colored portions, may be non-uniformly spaced about the periphery of the disc or drum, and the latter rotated at a speed in the order of seven revolutions per second. Although, for purposes of illustration, the irregularities on the tone wheels have been described as projections, it will be apparent that these irregularities may be in the form of notches or apertures of a wide variety of different shapes and conformations, and that in certain constructions, the pickup electrode, or scanning arm, may be rotated while the part corresponding to the tone wheel is held stationary. As an additional known equivalent construction, the tone wheel may be in the form of an apertured or notched dielectric disc.

In playing the instrument, the musician will actuate the keys in the manner of a piano. If the key is depressed slowly the rate of attack of the note will of course be correspondingly slow, and similarly, the rate of decay of the note is controlled by the rate at which the key is permitted to return to its normal position. As a corollary, the intensity of notes may be controlled by the extent to which the keys are depressed, and in this respect, the instrument will be responsive to the touch of the player in a manner similar to that obtained in the piano, with the additional

advantage that a tone may be made to continue to sound at any desired intensity level merely by holding the key depressed to the desired extent, with the result that organ-like tones may be produced.

It will be understood that the extent of depression of a key determines the degree of increase in the capacity of the condenser formed by the bus bar 20 and the flexible strip 24 attached to the key, and that the capacity of this condenser determines the amplitude of the radio frequency signal impressed upon the particular electrode or electrodes 54 which may be connected to the key. As a result, the radio frequency carrier wave, as modulated by the varying capacity between the electrode or electrodes 54 and their associated tone wheels 74, has its amplitude controlled by the extent of depression of the key. It will be understood that the tone wheels 74 may be made in any one of a variety of different forms, the essential requirement being that the tone wheel be capable, by its rotation, of slightly varying the capacity between it and its associated electrode 54.

In the course of playing the instrument, the vibrato effect may be increased, if desired, by adjusting the position of the shaft 132, if the construction of Figures 7 and 8 is employed, or by varying the position of the rheostat 144 if the electromagnetic system of Figures 9 and 10 is employed. As previously pointed out, the vibrato producing mechanisms of Figures 7 to 10 inclusive, cause alternate acceleration and retardation of the tone wheel carrying shafts, with the consequent introduction of a wide range of vibrato frequencies. Such wide vibrato is particularly useful in the rendition of music requiring string effects, but is generally advantageous in the rendition of any musical selection in which a rich full tone is desired to express warmth of feeling.

By means of the adjustable resonant output circuits 116, the tone color or timbre of the music produced, may be varied considerably to produce tones similar to those produced by various orchestral instruments. The tone color may of course also be varied by the use of a switching system of the general type illustrated in Figure 6, whereby depression of a single key will result in the transmission to the output of tone signals from a plurality of tone wheels. By thus supplying a large number of frequencies to the output upon depression of a single key, greater variations in tone quality are obtainable, especially in conjunction with the controls afforded by the adjustable resonant circuits 116.

When an ordinary radio receiving set is used in place of the radio frequency amplifier and detector shown as made particularly for the instrument, the intensity of the over-all output of the instrument may of course be controlled by the usual volume control device of the instrument, although ordinarily it will be desirable to provide an adjustable attenuation means, controlled by a swell pedal or the like, in the circuit between the tone wheel assembly and the radio receiving set. Similarly, when the instrument is thus used in conjunction with a radio receiving set, the adjustable resonant output circuits may be omitted. Furthermore, if desired, an amplifier and electromagnetic radiator may be connected to the conductor 169 so that there need not be any direct physical connection between the instrument and the radio receiving set.

It will be apparent to those skilled in the art

that numerous other variations and modifications of the invention may be made without departing from the underlying principle thereof. I therefore desire by the accompanying claims to include within the scope of my invention all such variations and modifications as will readily occur to those skilled in the art and by which substantially the results of my invention may be obtained by substantially the same means.

I claim:

1. In an electrical musical instrument, the combination of a tone wheel forming part of a signal generator, resilient means for driving said wheel at a speed in the order of seven revolutions per second, a member of magnetic material connected for rotation with said wheel, and means for exerting a magnetic accelerating force upon said member during a predetermined portion only of the rotative cycle of said member.

2. In an electrical musical instrument, the combination of a tone wheel forming part of a signal generator, a shaft for said tone wheel, resilient means to rotate said shaft at a speed in the order of seven revolutions per second, and means for exerting a retarding torque upon said shaft during a predetermined portion only of each rotative cycle of said shaft.

3. The combination set forth in claim 2 in which the means for exerting a retarding torque upon said shaft comprises a magnetic member secured to said shaft, and a permanent magnet having its magnetic field traversed by said member upon rotation of said shaft.

4. The combination set forth in claim 2 in which the means for exerting a retarding torque upon said shaft comprises a member of magnetic material secured to said shaft, and an optionally energized electromagnet having its magnetic field in the path of movement of said member upon rotation of said shaft.

5. In an electrical musical instrument in which the tone signals are electrically originated, the combination of a plurality of rotatable signal generators for producing electrical impulses of the frequencies of the different notes of at least an octave of the musical scale, and means for rotating all of said generators at speeds in the order of seven revolutions per second.

6. In an electrical musical instrument in which electrical impulses are originated under the control of keys, the combination of at least twelve signal pickup elements, a plurality of rotating members each having irregularities thereon rotated in paths passing close to one of said pickup elements respectively to produce electrical signals in the latter, and means to rotate all of said members at speeds in the order of seven revolutions per second.

7. The combination set forth in claim 6 wherein in the irregularities on said members are unequally spaced thereon.

8. The combination set forth in claim 6 in which the irregularities on each of said members are similar in conformation, but unequally spaced thereon.

9. The combination set forth in claim 6 in which the irregularities on each of said members are similar in shape, and in which approximately one half of the irregularities on each member are spaced closer together than the remaining irregularities thereon.

10. The combination set forth in claim 6 in which the irregularities on each of said members are similar in shape and in which each of said members forms one plate of a condenser, the

other plate of which is formed by its associated pickup element.

5 11. In an electrical musical instrument having a plurality of members, at least twelve in number, and each having irregularities formed thereon, a pickup element for each of said members, and means for rotating all of said members relative to said pickup elements at speeds in the order of seven revolutions per second, the irregularities on said members being spaced thereon at distances such that they will pass said pickup elements at average frequencies correlated respectively with the fundamental frequencies of the notes of the musical scale.

10 12. The combination set forth in claim 11 in which the irregularities on said members are in the form of projections spaced along the peripheries thereof.

15 13. The combination set forth in claim 11 in which each of said members has either five, six or eight irregularities formed thereon, or a number of irregularities which is a multiple of five, six or eight in which the multiplier is divisible by a power of two.

20 14. The combination set forth in claim 11 in which said members and their associated pickup elements form variable condensers, and in which there is a key controlled variable condenser connected to each of the pickup elements.

25 15. The combination set forth in claim 11 in which there is provided a source of radio frequency oscillations, key controlled means for selectively connecting said source to said pickup elements, and means for demodulating, amplifying and translating into sound the radio frequency signal which is modulated by said members.

30 16. A generating system for electrical impulses of a range of at least one octave for use as signal sources in an electrical musical instrument, comprising the combination of a plurality of tone wheels each having a plurality of irregularities which are non-uniformly spaced, means for rotating all of said wheels at speeds in the order of seven revolutions per second, and a pickup device cooperating with each of said wheels and affected by the passage of said irregularities past it and transducing such effect into an electrical signal.

35 17. A generating system for electrical impulses of a range of at least one octave for use as signal sources in an electrical musical instrument, comprising in combination, a plurality of tone wheels of electrically conductive material having projections on the peripheries thereof, said projections being non-uniformly spaced on each wheel to an extent such that the angular distance between some adjacent projections differs from the distance between other adjacent projections by an amount in the order of 3%, means to rotate all

40 of said wheels at speeds in the order of seven revolutions per second, and pickup electrodes respectively positioned closely adjacent the path of movement of the projections on said wheels.

45 18. A generating system for electrical impulses of a range of at least one octave for use in an electrical musical instrument comprising, the combination of a plurality of disc-shaped tone wheels each having unequally spaced projections along the periphery thereof, electrical pickup means located adjacent the peripheries of said wheels, and means for rotating said wheel past said pickup at speeds in the order of seven revolutions per second.

50 19. A generating system for electrical impulses

of a range of at least one octave for use as signal sources for electrical musical instruments comprising, a plurality of tone wheels each having a plurality of projections angularly spaced non-uniformly about its periphery, means to rotate said tone wheels about axes concentric with their peripheries at speeds in the order of seven revolutions per second, and electric pickup devices respectively located adjacent the paths of movement of the projections of said wheels.

20. In an electrical musical instrument in which are originated electrical signals of semi-tone frequencies extending throughout the range of at

least one octave, the combination of at least twelve stationary pickup elements, members each having a major component of motion of approximately seven cycles per second with respect to one of said pickup elements associated therewith, said members having irregularities affecting said pickup elements to produce electrical impulses in the latter, and means for causing an additional component of relative motion between said pickup elements and said members once during each cycle of said major component of motion between said members and said pickup elements.

LAURENS HAMMOND.
